UNITED STATES PATENT OFFICE.

WALTER F. STIMPSON, OF LOUISVILLE, KENTUCKY.

SCALE.

Application filed October 22, 1921. Serial No. 509,761.

The invention relates to scales and more particularly to that type known as "counter scales." Among the objects of the invention are; first, to obtain a sanitary construction which will permit of cleaning the counter beneath the scale; second, to completely house the levers and mechanism; third, to provide a stable support which is nevertheless, in effect, a three-point bearing facilitating the leveling of the scale; fourth, to condense the arrangement of the platform and supporting levers so that the base may be elevated from the counter without increase in the height of the platform; and fifth, to obtain a construction of pleasing appearance and one in which all of the parts are readily accessible, facilitating assembly and detachment for adjustment or repair. With these objects in view the invention consists in various features of construction as herein-after set forth.

In the drawings:

Figure 1 is a vertical central section through the scale;

Figure 2 is a plan view with the platform and a portion of the housing removed and the column shown in horizontal section;

Figure 3 is a vertical cross section through the column;

Figure 4 is a front elevation;

Figure 5 is a plan view;

Figure 6 is a detail view;

Figure 7 is a section on the line 7-7 of Fig. 2.

In the construction of counter scales, it is usual to provide a ring base for enclosing the platform levers, said base resting upon the counter and being covered by the platform. The clearance space between the platform

and this base ring will permit of a collection of dust and dirt which settles upon the counter and creates an unsanitary condition. With certain types of scale the base ring is slightly raised by supporting feet, but this

does not remedy the condition for the clearance is too slight to permit of cleaning beneath the scale. With my improved construction, in place of the ring base, I have provided a frame and housing for the platform levers which completely encases the same, but is cut away so as to provide space beneath the platform for cleaning. The lower portion of this housing is preferably rounded and by means of supporting feet it

is raised sufficiently above the counter to

provide abundant clearance for cleaning the same.

As specifically constructed, A is the platform supporting lever, preferably a lever of the third class having the wide portion A' to which the fulcrum pivots B are attached, the forwardly extending arms A² carrying the platform supporting pivots and the central rearwardly extending arm A³ which connects with the steelyard rod. C is the lower frame and housing member which surrounds the platform lever and which corresponds to the shape thereof. Thus at the front the housing member C is of a width to receive the portion A' of the platform lever, including the forward extensions A². At the center the member C is reduced in width, as indicated at C', merely providing a housing for the rearward extending portion A³ of the lever and at the rear the casing is enlarged at C² to form a support for the column. D is a complementary housing member arranged above the platform lever, being apertured at D' for the passage of the supporting legs E of the platform supporting frame E'. When the complementary portions C and D of the housing are placed together, they will completely enclose the platform lever. The lower section is raised by feet F and therefore the space beneath the frame and above the counter is easily accessible for cleaning.

G is the hollow column which is supported upon the portion C² of the base and which at its upper end is laterally extended at G' to support the cylinder housing H. The column G encloses the steelyard rod I as well as the dash-pot and other accessories and it is preferably made with transparent panels G², front and rear, through which the enclosed mechanism may be inspected.

The construction of base and platform above described can be used with various types of scales, either gravity-actuated or spring scales, but as specifically shown it is applied to the latter type. J are the weighing springs which are supported from a hanger K within the portion G' of the column and are attached at their lower ends to the steelyard rod I. This steelyard rod is preferably a bifurcated construction with a yoke I' at its lower end which is connected to the rearward extension A³ of the platform lever, while above this yoke the rod is laterally offset at I² to pass about the dash-

pot L. Above the portion I² is a bifurcated portion I³ which houses the lower part of the springs J. This portion I³ is provided at its upper end with a socket I⁴ in which a 5 single rod I⁵ is secured by a set screw I⁶. Between the furcations of the portion I³ is a downwardly extending link L' which is coupled to the stem L² of the dash-pot plunger. A screw cap L³ is carried by this stem, 10 and when the link L' is detached, this cap may be used for closing the cylinder of the dash-pot to prevent leakage of the fluid during shipment.

Within the cylindrical casing H is the 15 weighing and computing cylinder M, this being mounted upon a shaft M' journaled in anti-friction bearings at opposite ends of the casing H. The shaft M' has mounted thereon centrally thereof the pinion M² which engages a rack N pendant from the upper end 20 of the rod I⁵. The lower end of the rack has a rearwardly extending loop-shaped weight member N' which embraces the rod I⁵ and serves to yieldably press the rack against the pinion. Thus the movement of the platform 25 lever, which is transmitted by the steelyard rod, will effect a movement of the rack and a rotation of the pinion and cylinder M.

The platform supporting frame E' carries 30 the weighing platform O, this being preferably a glass plate. To hold the platform from tipping, a check rod is provided, this being connected to the rear end of the platform frame and rising vertically therefrom 35 in front of the column G. The upper end of this rod P enters the cylindrical housing H between sections of the computing cylinder M and at the upper end of the rod P is the rearwardly-extending portion P' to which 40 is attached the fitting P² for engaging the forwardly-extending check link P³. The forward end of this link is attached by a fitting P⁴ to a bifurcated segmental bracket arm Q mounted on the column and extending 45 between the cylinders M. Thus the check rod extends upward to nearly the center of the cylinder and by its relatively great length lessens the amount of friction and lateral oscillation due to the movement of 50 the platform.

The platform lever A is fulcrumed in a yoke member R which is mounted on lugs R', rising from the lower casing member C. R² are upward extensions of the member R at opposite ends thereof, which carry the bearings for the knife-edged fulcrum pivots. R³ are upward extensions from the central portion of the member R which embraces the cross bars A⁴ of the lever A and support 55 above the same the plate R⁴. On this plate R⁴ is arranged a level member R⁵ which is preferably circular in form and engages an aperture in the upper portion D of the level housing, so that the level will be visible 60 from above said housing. The level member

R⁵ has the usual transversely arranged level tubes and these are visible through the transparent platform and through an aperture E² in the platform supporting frame. The scale is leveled by a vertical adjustment of 70 the feet F which are provided with threaded stems that may be raised or lowered by turning.

To support the scale without rocking, a three-point bearing is desirable, but this does 75 not afford as great stability as where four points are used. I have provided a four-point support by placing the legs F under opposite sides of the wide portion of the 80 housings C and two legs beneath the column G. These latter supports are, however, connected to an evener lever S which is centrally fulcrumed within the base of the column, as indicated at S', thereby forming in effect a three-point support. However, 85 stability is obtained by limiting the independent movement of the legs F, which are attached to the lever S, so that a slight tipping of the scale will take up the lost motion and prevent further tipping. 90

It is usual to provide spring scales with a thermostatically controlled adjustment means for compensating for temperature changes. I have provided a construction of thermostatic control that is effective in its operation and easily applied to the scale. This consists in a thermostat T of the expansible chamber type, which is located between the cross bars A⁴ of the platform lever A. The forward end of this thermostat is rigidly attached to the lever, while the rear end is coupled to a rod T' passing rearward to a channel in the portion A³ of the lever. The rod T' is attached to an anti-friction carriage T² which has the pivot T³ connecting 100 with the steelyard rod. Therefore, whenever there is a rise in temperature, there will be a corresponding expansion of the thermostat T, which will carry the pivot T³ rearward, increasing the leverage of the arm A³. 105 On the other hand, a drop in temperature will contract the thermostat T and will decrease the length of the lever arm A³.

For setting the cylinder to the zero point when the platform is without load, provision 115 is made for raising and lowering the yoke K, which anchors the weighing springs J. This consists of a pair of rods U arranged on opposite sides of the springs J and extending from the yoke K downward into the 120 base. The lower ends of these rods rest upon a bifurcated rocker member V which has a downwardly extending arm V' adjacent to the end of a rod V² which passes centrally beneath the housing member C to the 125 forward end thereof. The rear end of the rod V² is threaded and engages a threaded aperture in a lug V³, while the forward end is swiveled in a lug V⁴ and is slotted to be turned by a screw-driver. The turning of 130

the rod V^2 in one direction will move it rearward and by engaging the arm V' will tilt the rocker V and raise the rods U . A rotation of the rod V^2 in the opposite direction

5 will produce the opposite effect and the lowering of the rods U . The movement of the rods U will raise or lower the yoke K and springs J , thereby effecting an adjustment of the cylinder M .

10 Variation in temperature will not only vary the tension of the weighing springs, but will also effect the adjustment of the indicator. This is compensated for by forming the rods U of a metal such as brass,

15 which, by its differential coefficient of expansion, will act as a thermostat. The fact that the rods U extend from the base to the cylinder housing gives a sufficient length to produce the compensation without the use 20 of levers or other complications and this greatly simplifies the construction.

As shown in Figure 6, the axis of the cylinder housing and of the cylinder is thoroughly offset from the center of the hollow 25 column. This gives a greater clearance for the check rod and the front of the cylinder housing and also by moving the cylinder housing and cylinder forward, brings the reading line so much nearer to the operator 30 in front of the scale.

What I claim as my invention is:

1. In a scale, the combination with a platform supporting lever, of a housing completely enclosing said lever, said housing including a pan shaped member having lower wall beneath said lever and a cover member for said pan shaped member enclosing said lever, and feet depending from said housing adapted to rest upon the counter or other 40 support, said feet projecting a sufficient distance below said bottom wall to provide adequate clearance beneath the housing for cleaning the counter.

2. In a scale, the combination with a platform supporting lever, of a housing for said lever including a pan shaped member extending beneath said lever and a complementary cover member extending above the same, a platform and a platform supporting frame above the housing having a plurality of supporting legs, the latter passing downward through apertures in the upper portion of said housing into engagement with the platform lever.

55 3. In a scale, the combination with a platform supporting lever, of a housing for said lever conforming to the general contour lines of said platform supporting lever and including a pan shaped member and a complementary cover member which together enclose said lever, said housing being provided with a lower wall beneath said lever, a plurality of bosses extending downwardly from said wall and feet below said 60 bosses, said bosses and feet being together

of sufficient height to raise said bottom wall considerably above the counter or other support thereby providing access for cleaning the counter beneath said lower wall.

4. In a scale, the combination with a platform supporting lever, of a housing for said lever conforming to the general contour lines thereof and having a wide front portion for the fulcrum and platform pivots, a narrow portion extending to the steelyard rod and an enlarged column supporting portion at the rear of said narrow portion, said housing including a pan shaped member and a complementary cover member for completely enclosing said platform supporting lever, and feet depending from said wide portion and said column supporting portion for raising the housing above the counter to provide access therebeneath for cleaning.

5. In a scale, the combination with a platform, of a platform supporting lever, and a housing for said platform supporting lever formed in complementary upper and lower sections, together completely enclosing 90 said lever and conforming to the general contour lines thereof.

6. In a scale, the combination with a platform, of a platform supporting lever having a wide front portion and a narrow portion extending to the steelyard rod, said wide portion being provided with rearwardly extending arms for the platform supporting pivots, and a housing having a wide portion surrounding the wide portion 100 of said platform lever, and a rearwardly extending narrow portion enclosing the narrow portion of said lever, said housing also being formed with a return-bend portion forming pockets adjacent said platform pivots and thereby conforming closely to the contour of said lever.

7. In a scale, the combination with a platform, of a platform supporting lever having a wide portion for the fulcrum and platform pivots, a narrow portion extending to the steelyard rod, a column enclosing said steelyard rod, and a housing completely enclosing said platform lever and conforming to the general contour lines thereof, said 110 housing having a wide portion, a rearwardly extending narrow portion and an enlarged column supporting portion, said housing also being formed with a return-bend portion forming pockets between the 115 wide and narrow portions of the housing adjacent said platform pivots.

8. In a scale, the combination with a platform, of a platform supporting lever having a wide front portion and a narrow rearwardly extending portion leading to the steelyard rod, said wide portion being also provided with rearwardly extending portions for the platform supporting pivots, and a housing enclosing said lever conforming 125 130

- to the general lines thereof having a narrow portion, a wide portion and a portion extending rearward from said wide portion.
9. In a scale, the combination with a platform, of a platform supporting lever having a wide portion and a narrow portion extending to the steelyard rod, a housing for enclosing said lever conforming to the general contour lines thereof, a hollow column supported at the end of the narrow portion of said housing, a cylinder housing at the upper end of said column, a platform supporting frame having downwardly extending legs passing through apertures in said housing, and a check rod for said platform supporting frame extending upward in front of said column and into the central portion of said cylinder housing.
10. In a scale, the combination with a frame, of a four-point support for said frame, and an evener between a plurality of the supports forming in effect a three-point support.
11. In a scale, the combination with a frame, of legs depending from said frame forming four-points of support, and an evener connection between two of said legs forming in effect a three-point support.
12. In a scale, the combination with a frame, of legs depending from said frame at four points, an evener connection between two of said legs having a central pivotal support, and means for limiting the rocking adjustment of said evener.
13. In a scale, the combination with a frame having a plurality of supporting legs, of an evener connection between two of said supporting legs provided with a central pivotal support.
14. In a scale, the combination with a platform, of a platform supporting lever, a housing for said platform supporting lever, including a removable cover for the same having an aperture therein, and a level mounted on the lower portion of said lever housing visible through said aperture in the cover portion thereof.
15. In a scale, the combination with a platform, of a platform supporting lever, a housing for said platform supporting lever conforming to the general contour lines thereof and comprising a lower section and a removable cover section provided with an aperture, a yoke member within the lower section of said housing forming the fulcrum support for said lever, and a level supported from said yoke above said lever, said level extending through the aperture in said cover section to be visible from without said housing.
16. In a scale, the combination with a transparent platform, of a supporting lever therefor, a housing for enclosing said supporting lever conforming to the general contour lines thereof, a platform supporting frame above said housing having depending legs extending through apertures therein, said frame being cut away to form an opening above said housing, and a level on said housing visible through said opening in said frame and the transparent platform.
17. In a scale, the combination with a platform, of a platform supporting lever, a housing for said platform supporting lever having apertures therein, a hollow column projecting upward from said housing, a cylinder housing at the upper end of said hollow column, a bifurcated cylinder within said cylinder housing, operating mechanism between said platform supporting lever and said bifurcated cylinder, a platform supporting frame having depending legs extending through the apertures in said housing into engagement with said platform lever, a check-rod extending upward from said platform supporting frame and into said cylinder housing, a bifurcated segmental member through which said check-rod passes, a lateral offset on said rod extending towards the center of said cylinder housing, and a check link extending between said laterally offset portion and said segmental portion, being also between the bifurcated cylinder.
18. In a scale, the combination with a platform, of a platform supporting lever, a housing for said platform supporting lever, a hollow column projecting upward from said housing, a cylinder housing at the upper end of said column, a bifurcated cylinder within said cylinder housing, operating mechanism between said platform supporting lever and said bifurcated cylinder, a platform supporting frame having depending legs supported upon said platform lever, a check rod extending upward from the rear side of said platform supporting frame and into said cylinder housing between the furcations of said cylinder, an arm on said check rod extending laterally towards the center of said cylinder housing, a segmental anchor arm extending from said column to the forward side of said cylinder housing, and a check link connecting said anchor arm to said lateral arm.
19. In a scale, the combination with a frame provided with a cylinder housing at its upper end, a bifurcated cylinder in said housing, a platform supporting lever operatively connected to said cylinder, a platform engaging said platform supporting lever, a check rod extending from said platform upward and into said cylinder housing between the furcations of said cylinder, a check link connected to said check rod and extending from near the center of said cylinder housing to the periphery thereof, and a segmental anchor arm connected at its lower end to said frame and at its upper end to said check link.
20. In a scale, the combination with a

- base, of a column extending upward from said base, a cylinder housing supported on the upper end of said column, a bifurcated cylinder within said cylinder housing, a platform supporting lever, a platform supporting frame engaging said lever, a check rod extending upward from said platform supporting frame into said cylinder housing between the furcations of said cylinder, an anchor bracket extending upward from said column, and a check link connecting said anchor bracket and the upper end of said check rod.
21. In a scale, the combination with a base, a hollow column extending upward therefrom, a platform supporting lever mounted on said base, a steelyard rod connected to said platform lever and extending upward within said hollow column, a platform supporting frame resting upon said platform lever, a check rod extending upward from said platform supporting frame, a cylinder operatively connected to said steelyard rod, and a cylinder housing therefor, the axis of said cylinder housing being laterally offset from the center of said hollow column, for the purpose described.
22. In a scale, the combination with a platform, of a platform supporting lever, a housing for said platform supporting lever formed in complementary upper and lower sections together completely inclosing said lever and conforming to the general contour lines thereof, and feet for raising said housing from the counter or other support to provide access to the space therebeneath for cleaning.
23. In a scale, a platform supporting lever, a pan shaped member in which said platform supporting lever is mounted, and a complementary cover member for said pan shaped member whereby said lever is enclosed.

In testimony whereof I affix my signature.

WALTER F. STIMPSON.
